PACKAGING CONTAINER FOR SEMICONDUCTORS OR THE LIKE

Thomas S. Jackson, Hopkinton, Mass., assignor to Expandex Corporation, Wauregan, Conn., a corporation of Connecticut

Filed May 22, 1961, Ser. No. 65,268

Term of patent 14 years

(Cl. D58—13)

FIG. 1

FIG. 3

FIG. 1 is a top plan view of a packaging container for semiconductors or the like, showing my new design; FIG. 2 is a side elevational view thereof; and FIG. 3 is an enlarged fragmentary perspective view of one of the compartments.

I claim:

The ornamental design for a packaging container for semiconductors or the like, as shown and described.
